LIQUID FUEL SUPPLY SYSTEM

Edward F. Martel, Lewiston, Maine, assignor of
one-third to James H. Duncan, Lewiston,
Maine

Application October 17, 1938, Serial No. 235,529

1 Claim. (Cl. 158—38)

This invention relates to a liquid fuel supply system for burners of ranges and similar devices wherein the burners are commonly supplied with fuel by gravity from a portable supply receptacle which must be frequently filled, and has for the primary object the provision of a system which may be readily connected with the burners, permitting the ordinary supply receptacle to become an auxiliary supply and which has a large capacity for fuel and will automatically supply the burners with fuel at a substantially constant level resulting in improved operation of the burners by producing a more uniform heat, the construction of the system being such that in case of temporary clogging or failure of flow of fuel from the source, the system will be automatically cut off to the burners for reducing fire hazards to a minimum and further through the use of this system the possibility of running out of fuel will be eliminated.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a diagrammatical view showing a liquid fuel supply system for burners and constructed in accordance with the present invention.

Figure 2 is a vertical sectional view illustrating the automatic means for maintaining a substantial constant level of fuel in the burners, and also including an automatic cutoff of the system.

Figure 3 is a fragmentary sectional view illustrating a part of the automatic cutoff.

Referring in detail to the drawings, the numeral 5 indicates a conventional type of liquid fuel burners wherein the fuel is supplied by gravity and must be kept at a substantial given level. The feed pipes for the burners 5 are indicated by the character 6 and have therein control valves 7. The feed pipes 6 are connected to a fuel supply pipe 8 leading to a fuel reservoir 9 supplied with fuel from a bottle type container 10. The construction described is conventional and it is well known that the container 10 has a very limited capacity for fuel, consequently needs refilling at frequent intervals. To eliminate this annoyance and to provide for better operation of the burners 5 the present invention is connected to the fuel supply pipe 8 and consists of a main fuel supply tank 11 located remotely to the

burners and in a plane above said burners and has an outlet pipe 11' connected to a combined filter and air vent tank 12. A cutoff valve is provided in the pipe 11', as shown at 13, and is of the manually actuated type. The combined filter and vent tank have connected thereto a vent pipe 14. Extending from the bottom of the combined filter and air vent tank 12 is a feed pipe 15. It will be seen that the fuel gravitates from the main supply tank 11 into the combined filter and air vent tank and from said tank into the fuel feed pipe 15. The fuel passing through the filter has foreign matter removed therefrom and the tank 12 being vented will prevent the system from becoming air locked.

The fuel feed pipe 15 extends downwardly and then horizontally and then up vertically to a selected height and again horizontally and is connected to a float tank 16 arranged vertically and located in a plane slightly below the last-named horizontal portion of the fuel feed pipe 15. The last-named horizontal portion of the fuel feed pipe 15 has therein a control valve 17 preferably of a needle type and manually operable so as to regulate the flow of fuel into the float tank 16.

The float tank 16 has a float controlled valve 18 to which the feed pipe 15 is connected. Also located in the feed pipe 15 adjacent to its connection with the float operated valve 18 is a safety cutoff valve 19. Operating in the float tank is a float 20 having a stem 21 operable in a guide 22 provided in the top wall of the tank. The stem 21 carries an arm 23 engageable with a float valve arm 24. The latter-named arm is pivotally mounted, as shown at 25, and has a limited slidable connection with the float valve 18, a spring 26 being interposed between the valve 18 and the lever 24. The spring 26 provides a yieldable drive between the lever 24 and the valve 18 to prevent jamming of the valve 18 against its seat by the float 20. The float 20 is provided with a guide stem 27 depending therefrom into an outlet pipe 28 of the float tank and carried by the upper end of the outlet pipe is a concaved baffle plate 29 forming the lower portion of the float tank into a sludge chamber 30 in which sediment and other foreign matter may accumulate. The baffle plate 29 is provided with openings 29' to permit the flow of fluid from the upper portion of the tank into the sludge chamber whereby sludge may accumulate therein. The float 20 maintains a predetermined level of fuel in the float tank.

The valve 19 is closed by the action of a torsion

type spring 31 and the stem of said valve has secured thereto an arm 32 having a head 33 at one end thereof adapted to engage with a trip lever 34 pivotally mounted on the float tank, as shown at 35. The trip lever is apertured to slidably receive the stem 21 of the float and mounted on the stem 21 at opposite sides of the trip lever are discs 36 which permit the float to have a limited movement in either direction before imparting pivotal movement to the trip lever 34 and freeing the arm 32 to allow the valve 19 to close. It is to be understood that the valve 19 is held in an open position by the arm 32 having the head 33 thereof in engagement with the trip lever 34.

The outlet pipe 28 of the float tank extends outwardly of the latter through the bottom thereof and is connected to the fuel supply pipe 8 as clearly shown in Figure 1 so as to maintain a predetermined level of fuel in the reservoir 9. This predetermined level of fuel is such that it will prevent fuel from passing into the reservoir 9 from the container 10, consequently permitting the fuel in the container to remain therein until such time that the fuel in the main tank 11 becomes exhausted or at a time when there is a failure of the fuel to flow through the present system to the fuel pipe 8.

As indicated in Figures 1 and 2 the maximum, normal and minimum fuel levels are indicated by horizontal lines and on the normal operation of this system the fuel is maintained in the burners between the minimum and maximum lines and any time that the fuel is consumed by the burners to bring the level slightly below the normal line the float automatically operates to admit fuel to the burners from the main supply tank 11. Should through some failure of proper operation of the system the float be caused to rise sufficient to admit to the burners an amount of fuel above the maximum level line, the float would automatically release the valve 19 and cut off the supply of fuel from the tank 11. This also applies should the level of the fuel in the burners fall below the minimum level line, the float automatically releases the cutoff valve 19. When the supply tank 11 becomes empty of liquid fuel and the fuel in the system arrives at a minimum operating level, as indicated in Figure 1, no further fuel will flow into the reservoir 9 and the latter is then fed with liquid fuel from the container 10 until the supply tank 11 is again filled. When the level of the fuel in the system reaches minimum operating level as indicated in Figure 1 the float will then have positioned the float actuated valve in an open position so that

when the supply tank 11 is again filled with fuel the fuel may flow through the system for filling the reservoir 9 to a normal level.

In operation it is preferable that the valve 17 be adjusted so that its orifice is smaller than the orifice provided in the float valve 18 to prevent any foreign matter traveling with the fuel from the main fuel tank 11 from entering and clogging the float valve 18. Any foreign matter that may pass through the valve 17 can easily pass through the float valve. Whenever the flow of fuel is stopped by clogging of the valve 17 the latter may be manually opened to a greater extent allowing the clogging material to be flushed on through to the float tank where it will be taken care of by the sludge chamber 30.

From the foregoing description it will be seen that through the use of this system the burners will be fed with fuel by gravity at a substantially constant level and that the fuel will be freed of all foreign matter and the system will be prevented from becoming air bound. As the fuel is fed to the burners strictly by gravity the cost of operation of the system is reduced to a minimum and also noise is eliminated.

It is believed that the foregoing description, when taken in connection with the drawings, will fully set forth the construction and advantages of this invention to those skilled in the art to which such a device relates, so that further detailed description will not be required.

Having thus described my invention I claim:

In combination with liquid fuel burners of the gravity feed type and a reservoir connected thereto for supplying fuel to the burners at a predetermined level and furnished with fuel from a liquid fuel container by gravity, a main fuel tank remotely located to said reservoir and at an elevation thereabove to feed fuel thereto by gravity, a pipe system connecting said tank to said reservoir for conveying fuel thereto by gravity, a float controlled tank connected in said pipe system and including a float actuated valve, a float for operating said valve for maintaining fuel at a predetermined height in the reservoir and at a height to prevent flow of fuel from said container to the reservoir, a self-closing cutoff valve located in said pipe system between the float valve and the main fuel tank, a trip mechanism for releasably securing the cutoff valve open, and means connected to said float for operating the trip mechanism to free said cutoff valve for closing by the float moving beyond a predetermined distance in either of the directions of travel thereof.

EDWARD F. MARTEL.
